SLIDER FOR SLIDE FASTENERS

Filed Aug. 23, 1940

UNITED STATES PATENT OFFICE

2,277,818

SLIDER FOR SLIDE FASTENERS

Alfred E. Carlile, Meadville, Pa., assignor to
Talon, Inc., a corporation of Pennsylvania

Application August 23, 1940, Serial No. 353,913

5 Claims. (Cl. 24—205.5)

This invention relates to slide fasteners and, in particular, to the provision of a new and improved slide fastener slider of the type illustrated and described in my copending application Serial No. 320,618, filed February 24, 1940 which matured into United States Letters Patent No. 2,223,279, granted November 26, 1940. This new and improved slider construction embodies a safety feature for preventing damage to the manually operable locking mechanism by the application of pressure to the locking apparatus.

In sliders of the above-described type, the locking operation is performed manually by swinging the pull tab down against the slider to force into the fastener member guide channel of the slider, a somewhat yieldable locking tongue member which is integral with the slider pull tab. Normally this tongue member rides or skids upon the flat side surfaces of the interlocking fastener members which it bridges when the slider is unlocked and it is necessary to force the locking tongue upwardly of the fastener toward more widely spaced or divergent fastener members, in the crotch of the fastener, in order that it may move inwardly of the plane of the aforesaid flat side surfaces of the fastener members into wedging engagement with the inclined surfaces of the fastener member head portions. This operation of the tongue member requires that it be yielding or resilient.

According to this invention, in order to protect this yieldable locking tongue member from damage and bending when pressure is applied to it in the extreme unlocked position of the pull tab, the pull tab is provided with supporting trunnions of limited section and strength which yield, or are partly sheared, upon application of damaging force to the pull tab, thus permitting sufficient inward movement of the pull tab for protection of the upraised locking tongue by the pull tab supporting lugs at opposite sides of the pull tab, which lugs cooperate with the trunnions to attach the pull tabs to the slider body.

This yielding, or shearing, of the pull tab supporting trunnions is achieved by reduction of the section of the trunnion end portions in order that they may become partially sheared upon application of dangerous pressure to the locking tongue, to permit the pull tab to move inwardly of the slider to place the uppermost part of the locking tongue between and below the upper surfaces of the lugs which then take the total applied pressure.

These trunnion end portions of reduced section (which may be termed "frangible" trunnion

end portions) before they are partially sheared, retain the slider pull tab against objectionable movement inwardly of the slider channel, whereby to prevent inward displacement of the pull tab and consequent difficulty in assembling the slider to the stringers of a slide fastener. The lugs, however, are engaged by portions of the pull tab trunnions which are disposed inwardly of these frangible trunnion end portions, which portions are unaffected by the above-described shearing of the frangible trunnion end portions. Thus displacement of the pull tab outwardly of the slider channel is prevented irrespective of shearing of the frangible trunnion end portions, while entry of the pull tab into the slider channel is blocked by the interlocking fastener members in the slider channel, after the slider is assembled to the stringers of the slide fastener.

In addition to the above-described function of the frangible end portions of the pull tab supporting trunnions, these trunnion end portions facilitate assembly of the pull tab to the supporting lugs of the slider body according to the new and improved method of slide fastener slider pull tab assemblies, comprising a part of this invention, which is herein described and illustrated. In this method the supporting lugs of the slide fastener slider body are formed spread apart to a degree sufficient to permit insertion of the pull tab trunnions thereunder, whereafter side pressure is applied to the trunnions to raise or bring them upright with relation to the slider body whereby they are brought into substantial parallelism with the pull tab trunnions retained pivotally between them and the slider body proper, permanently to secure the pull tab in its operative relationship on the slider.

In the drawing:

Fig. 1 is a fragmentary view, in perspective, of a conventional slide fastener embodying a slider constructed according to this invention, a part of the pull tab being broken away in the interest of clearness of disclosure;

Fig. 2 is a transverse section taken substantially on the line 2—2 of Fig. 1;

Fig. 3 is a fragmentary enlarged section similar to Fig. 2, but showing the slider assembled to the stringers of a slide fastener and illustrating the application of pressure substantially vertically of the slide body;

Fig. 4 is a section taken substantially on the line 4—4 of Fig. 3;

Fig. 5 is a section taken substantially on the line 5—5 of Fig. 3;

Fig. 6 is a fragmentary transverse section illus-

trating the initial step in assembling the pull tab to the slider body; and

Fig. 7 is a view similar to Fig. 6, but illustrating a subsequent step in the method, wherein the pull tab retaining lugs of the slider body are raised or bent upwardly into substantial parallelism.

Referring to the drawing in detail, the conventional slide fastener shown in Fig. 1 for the purpose of illustration only, comprises a pair of stringers generally designated 10, connected at their lower ends by a conventional bottom stop 11 with a slider 12 constructed according to this invention, slideable on the rows of spaced cooperating interlocking fastener members of the stringers 10. Each stringer 10 comprises a tape 14 with a reinforced edge 15, upon which reinforced edge 15 is a row of predeterminedly spaced interlocking fastener members 16, secured thereto in conventional manner. The slider 12 is provided with a pull tab member generally designated 17 which is pivotally secured thereto and by means of which it is moved longitudinally of the stringers 10 in opposite directions, for opening and closing the fastener in known manner.

The body of the illustrated slider comprises a front wing member 18 and a rear wing member 19 which are secured together at their upper ends, in predetermined spaced relation, by a wedge member or neck member 20. The wing members 18 and 19 are provided with similar side flanges 21 extending inwardly of the space between the wing members 18 and 19. These side flanges 21 cooperate with the side surfaces of the wedge or neck member 20 to form a substantially Y-shaped upwardly diverging guide channel for the interlocking fastener members 16. The adjacent side flanges 21 are slightly spaced to form slots 22 through which the tapes 14 extend in opposite directions.

While the front and rear wing members 18 and 19 are of like shape and size, the front wing member 18 is provided with an aperture 24, the side portions of which are formed by the space provided in the front wing member by the striking up of the pull tab supporting lugs 25. These lugs 25 are of substantially U-shaped longitudinal section in the finished, assembled, slider. The intermediate portion of the aperture 24, between the lugs 25, extends downwardly of the front wing member 18, slightly beyond the lower end of the lugs 25, as shown at Fig. 5. Thus, the lugs 25 overlie the side portions of the aperture 24 and are disposed inwardly of the sides of this aperture. In other words, the lugs 25 are, necessarily, more closely spaced than are the sides of the aperture 24.

While it was formerly general practice to form the pull tab supporting lugs in their final position, or substantially perpendicular with respect to the front wing member 18 before assembly of the pull tab member to the slider, or in the position shown in Figs. 2, 3 and 7, according to the principles of this invention, they are formed in the position shown in Fig. 6 prior to assembly of the pull tab thereto and thereafter, as is hereinafter more clearly explained, brought to the position of Fig. 7 from that position shown in Fig. 6.

The pull tab member 17 is preferably formed from strip material and comprises a handle portion 26 of plate-like form having therein an aperture 27 adapting it for the attachment of thongs, ribbons, or the like. Extending downwardly from the lower or inner end of the plate-

like handle portion 26 is a reduced neck portion 28 having extending from opposite sides thereof trunnions or pivot pins 29 having reduced end portions or extremities 30.

The combined width of the trunnions 29 and the intermediate neck portion 28 is slightly greater than the width of the aperture 24. This difference in width is, however, so slight that only the reduced end portions 30 of the trunnions 29 rest upon the side edges of the aperture 24 in the front wing member 18 to prevent the pull member 17 from becoming accidentally displaced inwardly of the slider and from entering the slider channel upon assembly of the slider, as shown in Figs. 1, 2, 5 and 7. These reduced end portions may be termed "frangible" trunnion end portions because of their function, as will hereinafter most clearly appear. Following assembly of the pull tab member to the slider body, the initial function of these frangible trunnion end portions is thus to prevent accidental displacement of the pull tab member 17, especially before the slider is assembled to the stringers of a slide fastener. As will clearly appear from Figs. 2, 3 and 5, the main portions of the trunnions 29 underlie the lugs 25, whereby retention of the pull tab member 17 against displacement outwardly of the slider body is effected totally independently of these frangible trunnion end portions.

As shown in Figs. 1 and 4, a bent-up tongue member 31 of buttonhook like section extends downwardly or inwardly from the neck portion 28 of the pull tab member 17 and this locking tongue member 31 is of less width than the distance between the lugs 25, as shown in Figs. 2, 3, 5 and 7. Because of this relationship, the locking tongue member 31 may move freely between the lugs 25 and through the central portion of the aperture 24 into and out of the fastener member guide channel of the slider 12. The initial shape of the locking tongue member 31 is such that it projects above the lugs 25 when the pull tab member is swung downwardly against the slider body in the fully unlocked position, as shown in Figs. 1 and 2. This projection of the locking tongue member 31 above the lugs 25 subjects it to initial contact with flatirons and other pressing devices indicated at 32 in Figs. 3 and 4, when such devices are used to press a garment embodying the fastener, of which the slider 12 and its pull tab member 17 are a part.

Where, as is described in my copending application Serial No. 320,618, the trunnions of the pull tab member are unyielding, the application of pressing force initially to the locking tongue member 31 will cause the locking tongue member 31 to be bent inwardly of the slider and toward the handle portion 26 of the pull tab member 17 to such degree as substantially to impair the effectiveness of its operation as locking means for the slider. As is explained in the above-identified application Serial No. 320,618, it is necessary that this locking tongue member 31 be resilient or springy in order to accomplish its intended function.

By reducing the section of the trunnion end portions 30, the bending of the locking tongue member 31 under the influence of such pressing force is reduced to a minimum because, as is clearly shown in Figs. 3 and 4, the application of pressure downwardly upon the pull tab member 17 and its locking tongue member 31 will cause the relatively sharp side edges of the aperture 24 to bite into, cut into, or shear the trun-

nion end portions 30 of reduced section until the downward force exerted by the pressing device 32 is taken substantially completely by the upstanding pull tab retaining lugs 25, as shown in Figs. 3 and 4. In other words, the weakening of the trunnion end portions or extremities 30 will cause them to be sheared to a degree sufficient to permit necessary retraction of the locking tongue member 31 below the top surfaces of the pull tab retaining lugs 25, which insures retention in the locking tongue member 31 of its proper contour and resiliency whereby it may operate with utmost efficiency in the manner which is intended as is clearly described in the above-identified application Serial No. 320,618.

As will clearly appear from Fig. 5, the width of the plate-like handle portion 26 of the pull tab member is the ultimate width of strip stock necessary for cutting out or stamping out the pull tab member 17 prior to bending up the locking tongue member 31 to its final shape. In prior pull tab constructions, as illustrated in my application Serial No. 320,618, it was necessary that the pull tab stock be substantially wider to make it possible to cut out or stamp out the pull tab members with out-spread legs projecting sideways, in either direction, for a substantial distance. These legs were thereafter clamped or clenched inwardly until trunnion projections at their ends extended inwardly under the upstanding pull tab retaining lugs on the slider body. Thus, the illustrated pull tab construction, in addition to incorporating in the slider the above-described safety feature, also substantially reduces the cost of production by reducing the width of the strip stock necessary for production while reducing scrap loss.

In addition to the above advantages, this pull tab construction lends itself to the new and improved method of pull tab assembly illustrated in Figs. 6 and 7, wherein the lugs 25 are initially formed at an outward inclination to their final position, the planes thereof being inclined substantially 70 degrees from one another and in which method one of the trunnions 29 is swung into the position shown in Fig. 6 and thereafter to the position shown in Fig. 7, subsequent to which alignment of the pull tab member 17, oppositely directed transverse forces are applied by suitable means such as side tools 33 to force the pull tab retaining lugs 25 upwardly to their final position, wherein they are in substantial parallelism.

From the above description, it will clearly appear that I have provided a new and improved manually operated lock slider for slide fasteners of the type described and illustrated in my application Serial No. 320,618, which new and improved slider construction embodies as an important part thereof a pull tab construction achieving economy of material, with extremely high resistance to damage by pressing because of the safety feature embodied by the frangibility of the trunnion end portions, and that I have also provided a new and improved method of assembling pull tab members to slide fasteners which makes possible the complete preforming of the pull tab constructions of the type described and illustrated whereby the strength thereof may be substantially increased over prior locking pull tab members of the same general type without, in any way, increasing, but on the other hand, decreasing difficulty of the pull tab attaching operation.

It is, of course, to be understood that the above 75

description is merely illustrative and in nowise limiting and that I desire to comprehend within my invention such modifications as are included within the scope of the appended claims.

Having thus fully described my invention, what I claim as new and desire to secure by Letters Patent is:

1. In a slider for slide fasteners, a slider body comprising a pair of connected wing members 10 with a fastener member guide channel therebetween, one of said wings having therein an aperture communicating with said channel, a pair of pull tab retaining lugs overlying said aperture at opposite sides, and a pull tab member 15 hinged to said slider body and comprising a plate-like member having a pair of oppositely directed trunnions extending transversely outwardly from its inner end and disposed beneath said lugs, said trunnions having end portions of reduced section extending beyond the side edges of said aperture and capable of yielding upon application of destructive pressure to said pull tab and accommodating movement of the inner end of said pull tab inwardly into said aperture for protecting said pull tab member against destructive deformation.

2. In a slider for slide fasteners, a slider body comprising a pair of connected wing members 30 with a fastener member guide channel therebetween, one of said wings having therein a locking member accommodating aperture communicating with said channel, a pair of pull tab retaining lugs overlying said aperture at opposite sides, and a locking pull tab member 35 hinged to said slider body and comprising a plate-like member having a locking member at one end projectable through said aperture and a pair of oppositely directed trunnions extending outwardly transversely therefrom and disposed beneath said lugs, said trunnions having end portions of reduced section extending beyond the side edges of said aperture and capable of yielding upon application of destructive pressure to said locking member and accommodating inward movement of the inner end of said pull tab member into said aperture for protecting said locking member against destructive deformation.

3. In a slider for slide fasteners, a slider body comprising a pair of connected flanged wing members 50 defining a fastener member guide channel therebetween, one of said wings having therein a locking member accommodating aperture communicating with said channel, a pair of pull tab supporting retaining lugs overlying said aperture at opposite sides, and a locking pull tab member 55 hinged to said slider body and comprising a plate-like member having a locking member at its inner end projectable through said aperture into locking engagement with fastener members in said channel and a pair of oppositely directed trunnions extending transversely outwardly therefrom adjacent said locking projection and disposed beneath said lugs, said trunnions overlying said aperture and extending beyond the side edges thereof and the section of the trunnion end portions extending beyond the side edges of said aperture being reduced and capable of being sheared, at least partially, upon application of destructive pressure to said locking member and said pull tab for protecting said locking member against destructive deformation.

4. As a new article of manufacture for use as a pull tab on a slide fastener slider having a pair of transversely spaced pull tab retaining lugs and an aperture extending between and beneath said

lugs, a plate-like member having a handle portion defining the greatest width of said member, an end portion of reduced width approximately equalling the spacing between said lugs, and a pair of oppositely outwardly directed trunnions extending from said last-named portion, the combined width of said trunnions being less than the width of said handle portion and greater than the width of said aperture.

5. As a new article of manufacture for use as a locking pull tab on a slide fastener slider having a pair of transversely spaced pull tab retaining lugs and a locking member accommodating aperture extending between and beneath said lugs, a member having a handle portion defining 10 the greatest width of said member, an end por-

15 tion of reduced width approximately equalling the spacing between said lugs, a pair of oppositely outwardly directed trunnions extending from said last-named portion, the combined width of said trunnions being less than the width of said handle portion and greater than the width of said aperture, and a locking member on said end portion of less width than said aperture and projectible therein, the end portions of said trunnions having reduced section in order to be sheared by the aperture side edges upon application to said pull tab of pressure directed toward said slider for preventing application of destructive pressure to said locking member.

ALFRED E. CARLILE.
